US00D376430S

United States Patent

[19]

Humphrey et al.**Patent Number: Des. 376,430****Date of Patent: **Dec. 10, 1996**[54] **NURSER BOTTLE**

[75] Inventors: **David C. Humphrey**, Fremont, Mich.;
Brenda J. Meyers; **Donald W. Herritz**, both of Reedsburg, Wis.

[73] Assignee: **Gerber Products Company**, Fremont, Mich.

[**] Term: **14 Years**

[21] Appl. No.: **41,837**

[22] Filed: **Jun. 26, 1995**

[52] U.S. Cl. **D24/197**

[58] Field of Search D24/197; 215/11.1, 215/11.2, 11.3, 11.4, 11.5, 11.6

[57] **CLAIM**

The ornamental design for the nurser bottle, as shown and described.

DESCRIPTION

FIG. 1 is a top perspective view of the nurser bottle, showing our new design, the broken line showing is for illustrative purposes only and forms no part of the claimed design;

FIG. 2 is a left side elevational view of FIG. 1, the right side elevational view being a mirror image of that shown;

FIG. 3 is a front elevational view of FIG. 1;

FIG. 4 is a rear elevational view of FIG. 1;

FIG. 5 is a top plan view of FIG. 1; and,

FIG. 6 is a bottom plan view of FIG. 1.
